Inventor:
Michael Renner,

by *Michael S. Renner*
His Attorney.

UNITED STATES PATENT OFFICE.

MICHAEL RENNER, OF SCOTIA, NEW YORK, ASSIGNOR TO GENERAL ELECTRIC COMPANY, A CORPORATION OF NEW YORK.

VACUUM TUBE.

Application filed April 21, 1927. Serial No. 185,548.

The present invention relates to vacuum tubes and more particularly to suspension means for supporting the cathode element in such tubes. One of the objects of the invention is to provide a resilient cathode support which is so mounted in the vacuum tube that lateral movement of the cathode is prevented.

In the construction of vacuum tubes the amount of space between the cathode or filamentary electrode and the grid or control electrode is very limited and it sometimes happens that when the filament is heated or subjected to vibration it will contact with the grid and thereby interfere with the operation of the tube. Heretofore, it has been proposed to provide a suspension element for the filament which comprises a wire extending through a rigidly supported insulator, one end of the suspension element being provided with a hook adapted to engage the filament, and the other end of the suspension means being engaged by a spring supported on the insulator. As thus arranged, however, the opening in the insulator has to be made quite large to provide for free movement of the suspension means under all conditions and especially when the filament is heated. Making the opening in the insulator sufficiently large to provide for free movement of the suspension means permits the suspension means to pivot about the opening in the insulator and thereby allow sufficient lateral movement of the filament to short circuit the filament on the grid. According to the present invention this pivoting movement of the suspension means has been prevented by the presence of a second insulator spaced from the first insulator and provided with an opening adapted to slidably engage the upper end of the suspension means thereby effectively preventing lateral movement of the suspension means and cathode.

The novel features which I believe to be characteristic of my invention are set forth with particularity in the appended claims. My invention itself, however, will best be understood from reference to the following specification when considered in connection with the accompanying drawing in which Fig. 1 shows a front elevation partly broken away of a vacuum tube embodying the features of my invention while Figs. 2 and 3 are respectively a perspective detailed view

and a cross sectional detailed view of the means for supporting the filamentary cathode, Fig. 3 being on a somewhat enlarged scale.

Referring to the drawing, I have indicated at 1 a vacuum tube of well known construction in which the anode 2 is supported on a split metal collar 3 mounted at one end of the tube while the filamentary cathode and grid are supported from the opposite end of the tube. An insulator 4 is mounted on the collar 3 and is provided with openings 5 adapted to accommodate rods 6 which serve as a support for the grid or control electrode. Engagement of the rods 6 in these openings prevents lateral movement between the anode and control electrode. A second insulator 7 is mounted on rods 6 and held in position by small metal beads or other suitable means. Insulator 7 is provided with a plurality of openings 8 adapted to slidably accommodate suspension wires 9 each of which has a hook 10 at its lower end adapted to engage a filamentary cathode 11. A metal plate 12 having a downwardly extending flange 13 is rigidly secured to wire 9 by means of a perforated plate 14 which is welded to wire 9 and plate 12. A second metal plate 15 rests on insulator 7 and fits loosely on wire 9. Plate 15 is provided with an upwardly extending flange 16 as clearly indicated in Fig. 3. A cylindrical spring 17 is mounted between plates 12 and 15 and is normally held compressed by the tension of the filament 11. The flanged plate 15 prevents lateral movement of spring 17 and holds it in central position with respect to wire 9.

A third insulator 18 mounted on rod 6 and disposed between insulators 4 and 7 is normally spaced from the latter by a plurality of metal collars or sleeves 19 mounted on rod 6. Metal beads 20 serve to maintain insulator 18 in spaced relation with insulator 4. Insulator 18 is provided with a plurality of openings 21 in alignment with openings 8 in insulator 7 and adapted to accommodate wires 9.

The spacing collars 19 are of such a length that the maximum upward movement of the plate 12 due to expansion of the filament when heated, will carry the plate to a point just short of insulator 18. The distance between insulators 4 and 7 is sufficient to per-

mit maximum upward movement of wire 9 without causing contact of wire 9 with insulator 4.

- 5 Spring 17 on account of its cylindrical shape and the bearings provided by the plates 12 and 13 causes movement of the wire 9 in a substantially vertical direction and thereby tends to prevent binding of wire 9 in the openings 8 and 21. However, if 10 there is any tendency for lateral movement of the lower end of wire 9, such movement is effectively prevented by the engagement of the upper end of this wire with the sides of the opening 21 in insulator 18.
- 15 15 What I claim as new and desire to secure by Letters Patent of the United States is:
1. In an electric discharge device, a rigidly mounted insulator provided with an opening, a wire extending therethrough, 20 said wire having means at its lower end adapted to engage a filamentary electrode, flexible means engaging said wire whereby a tension may be applied to the filament, and means slidably engaging the upper end 25 of said wire and adapted to limit lateral movement of said filamentary electrode.
  2. In an electric discharge device, a pair of rigidly mounted insulators spaced apart from one another and provided with aligned 30 openings, a wire extending through said

openings and adapted to engage a filamentary electrode, and a spring mounted between said insulators and connected to said wire.

3. In an electric discharge device, a pair 35 of rigidly mounted insulators spaced apart from one another and provided with aligned openings, a wire extending through said openings and adapted to engage the cathode element of the discharge device, a plate rigidly connected to said wire, and a spring mounted between said plate and one of said insulators.

4. In an electric discharge device, a rigidly mounted insulator having an opening 45 extending therethrough, a plate having an opening in alignment with the opening in the insulator, said plate having an upwardly extending flange, a wire extending through said openings, said wire having a hook at its 50 lower end adapted to engage a filament, a plate having a downwardly extending flange rigidly secured to said wire adjacent the upper end thereof, and a substantially cylindrical spring mounted between said plates 55 and adapted to apply tension to the filament.

In witness whereof, I have hereunto set my hand this 20th day of April, 1927.

MICHAEL RENNER.
